UNITED STATES PATENT OFFICE.

GEORGE THOMPSON COOLEY, OF JOPLIN, MISSOURI.

ORE-CONCENTRATOR.

1,323,157.

Specification of Letters Patent.

Patented Nov. 25, 1919.

Application filed November 13, 1915. Serial No. 61,274.

To all whom it may concern:

Be it known that I, GEORGE T. COOLEY, citizen of the United States, residing at Joplin, in the county of Jasper and State of Missouri, have invented certain new and useful Improvements in Ore-Concentrators, of which the following is a specification.

My invention relates to an improvement in ore concentrators and the present invention is intended to do its work under water.

The object is to provide a machine which is adapted for the concentration of all kinds of ores, my intention being to not only provide a machine of universal application but also one which will practically effect a 100% saving of values.

This I accomplish in the main through the instrumentality of three motions, to wit: a jig motion, a table motion and a pan motion, and especially constructed riffles, the ore working down the inclined sides of and lodging in the bottoms of the riffles, due to stratification, whence it is carried forward through the machine and drawn off through the valves for that purpose.

The accomplishment of these objects is obtained through a number of mechanical instrumentalities which combine and coöperate with one another and which will be hereinafter fully described and pointed out in the claims.

In the accompanying drawings:

Figure 1 is a view in perspective;

Fig. 2 is a vertical longitudinal section, the center of the machine being broken out;

Fig. 3 is a view in perspective of the crow foot toggle, enlarged;

Fig. 4 is a sectional view of the elevator;

Fig. 5 is a vertical transverse section;

Fig. 6 is a view in perspective of a portion of the operating mechanism;

A represents the main frame of the machine and B is the concentrator. The bottom of the concentrator is in the form of inclines 1 and riffles 2 which extend throughout the length of the concentrator and to which the inclines lead.

The concentrator is supported at one end upon the crow foot toggle 3, the tenon 4 of which enters the mortise 5 of the plate 6 in the rocking of the toggle, and the toes 7 of which strike the plate abruptly at either end of the mortise causing the table to rise and fall with more or less jar at the end supported by the crow foot toggles.

The other end is supported on a many-

sided roller 8. This roller preferably has 16 faces and the trunnions 9 at its ends are journaled in notches 10 in the cage 11 and the elevation of the concentrator B is regulated by adjusting this roller in notches higher or lower down in the cage, and the reciprocating movement which is imparted to the concentrator causes a trembling action to the table at the discharge end which is necessary in order to settle all kinds of ores which are heavier than their gangues.

A wedge block 12 on the inner face of the post 13 has an inclining outer edge which engages a similar wedge 14 on the table 70 which latter imparts side or lateral motion to the table as it reciprocates, thus providing the pan motion so essential in the concentration of most ores.

At the feed end of the table the screen 15 is placed and into this the material to be operated upon is delivered. The over size passes over the screen and drops out and the material that passes through the screen falls down the incline 16 into the bottom of the concentrator table or bed B, through which it is swept by the scrapers 17 carried by sprocket chains 18 over sprocket wheels 19 and 20.

A baffle board 21 at the discharge end is adjustable and is adapted to be placed about 6 inches from the bottom of the concentrator B, its function being to cause the ore to pass beneath, thus preventing any from floating to the surface. An elevator 22 revolves at the discharge end and sweeps out the tailings which are discharged at the outlet 23 while the values continue on beneath the shield or plate 24 to the ends of the riffles 2, discharging finally through the valves 25.

The elevator is of very simple construction and may be made of a 6 by 6 block of wood with strips nailed thereto as shown in detail in Fig. 4 and while its dimensions may, of course, be varied, it is preferably about 30 inches in diameter in a full sized machine, and it effectually sweeps the discharge end of the concentrator which is curved in the arc in which the elevator turns so that the wings of the elevator sweep the bottom and keep it clear of tailings.

Motion to all parts is imparted through the drive shaft 26 which is journaled in bearings at the end of the frame A and which has eccentricities 27 thereon which drive 110 and reciprocate the connecting rods 28 which extend to the crow foot toggles 3 and oscil-

late the latter, power being applied to the drive shaft 26 through the wheel 29.

A sprocket chain 30 extends over a sprocket wheel 31 on drive shaft 26 from which point 5 it passes over a sprocket wheel 32 on the shaft 33 and the drag line chains 18 pass over wheels 34 and 35 carried on this shaft 33 and also over wheels 36 and 37 carried by shaft 38, and the chain 39 extends over a 10 sprocket wheel 40 on the end of shaft 33, over a sprocket wheel 41 on shaft 42 and around sprocket wheel 43 on shaft 38, and a sprocket chain 44 extends over a sprocket wheel 45 on the opposite end of shaft 42 15 from wheel 41 to a sprocket wheel 46 on the shaft which drives the elevator.

The machine is so geared that the drag lines including the scrapers cross the machine five times per minute; the gangues 20 do not have to be washed and there is no end to the capacity. The elevator oscillates with the machine and consequently when on dead center the elevator wheel 22 is in line with the drive shaft 42 above so it only 25 plays on both sides of the center about one inch which does not make any material difference in the sprocket chain. The scrapers by traveling across the machine to the tail end keep all material loose at the bottom at 30 all times so that the stratification can easily take place, thus avoiding the danger of its becoming packed and leathery, which retards concentration.

The machine has from $1\frac{1}{2}$ to a 3 inch 35 stroke, this depending on the ore being treated as well as the capacity at the last $\frac{1}{2}$ inch of the stroke, and the wedge blocks 12 and 14 impart a side swing to the machine at the discharge or tail end which is 40 very effective and keeps the ore from packing the valves.

The roller 8 is set in a higher or lower notch 10 in accordance with the ore being treated. For instance, when a thin ore is 45 being treated the roller is set in a lower notch giving the concentrator more fall or slip making the bed steeper and causing the material to travel faster and in this way it has greater capacity.

50 It is doubtless understood that water is not used as in a jig or an ordinary concentrator table, for the water in this machine does not flow off of the machine. It simply requires enough water to keep the ore saturated which is not over one-fifth as much water to handle a ton of ore as in a jig or concentrator table.

The crow foot toggle causes the front end of the bed to pump up and down approximately $\frac{3}{4}$ of an inch while it glides about 2 inches and the flat-faced roller 8 gives the bed about $\frac{1}{16}$ inch up and down motion at the tail end with the same glide that the head end has, whereas the wedge blocks 12 65 and 14 give it a side or lateral motion of

say $\frac{1}{2}$ inch and with these three motions combined it is impossible for ore to escape settling and the drag lines deliver the tailings to the elevator wheel and out, the ore slipping from the apexes on the bottom 70 down the inclines 1 into the riffles 2, aided by the motion of the crow foot toggles, and after lodging in the riffles the concentrates travel to the discharge end under the shield 24 and out through the valves 25. 75

The crow foot toggle also imparts a jarring motion to the screen which keeps the material fed into it from binding and clogging.

Obviously the size and capacity of the 80 machine may be indefinitely varied and I propose to make it from 3 to 8 feet wide and about 10 feet in length and with the fulcrum provided by the crow foot toggle the machine is rendered very easy and light 85 to operate.

I claim:

1. The combination with a main frame, a concentrator the bottom of which concentrator is in the form of transverse inclines, 90 riffles which extend longitudinally of the concentrator, means for constantly reciprocating the concentrator and means for jarring the concentrator upwardly as it reciprocates, of scrapers which sweep over the 95 riffles from the feed toward the discharge end of the concentrator, endless chains to which the scrapers are attached, and means for carrying and for driving said chains.

2. The combination with a main frame 100 and a longitudinally riffled concentrator, of means for reciprocating the concentrator lengthwise the riffles, traveling scrapers which constantly sweep the riffles from one end to the other, and means at each end of 105 the concentrator for imparting a trembling or jarring motion thereto as the concentrator reciprocates.

3. The combination with a main frame and a longitudinally riffled concentrator, of 110 means for reciprocating the concentrator lengthwise the riffles, traveling scrapers which constantly sweep the riffles from one end to the other, and three independent means which impart unitedly an upward and downward movement to the opposite ends of the concentrator and a lateral motion thereto.

4. The combination with a main frame and a riffled concentrator, of means for reciprocating the table lengthwise of the 120 riffles, means at each end of the table for imparting a trembling or jarring up and down motion thereto, and means at one end for imparting a lateral jarring motion to 125 the table as it is reciprocated lengthwise.

5. The combination with a main frame and a concentrator, the bottom of which is in the form of inclines and riffles extending lengthwise thereof, of means for reciprocating 130

ing the table lengthwise of the riffles, means at each end of the table for imparting a trembling or jarring up and down motion thereto, the means for imparting a trembling motion at one end comprising a crow-foot toggle pivoted or hinged to the concentrator and the frame provided with a mortise to receive said crow-foot toggle whereby to cause the concentrator to be alternately

jarred up and down with the vibrations of 10 the toggle due to the endwise reciprocation of the concentrator, and scrapers for constantly sweeping the riffles lengthwise.

In testimony whereof I affix my signature.

GEORGE THOMPSON COOLEY.
